(57) **CLAIM**

The ornamental design for an indoor wall incorporated with built-in home appliances, as shown and described.

DESCRIPTION

1. Indoor wall incorporated with built-in home appliances

1.1 : Perspective

1.2 : Front

1.3 : Back

1.4 : Left

1.5 : Top

1.6 : Bottom

1.7 : Exploded

1.8 : Perspective view 2

1.9 : Front view 2

1.10 : Back view 2

1.11 : Left view 2

1.12 : Top view 2

1.13 : Bottom view 2

1.14 : Reference view

The broken lines depict portions of an indoor wall incorporated with built-in home appliances that form no part of the claimed design; reproductions 1.1 to 1.7 are front perspective, front, back, left, top and bottom views of the indoor wall incorporated with built-in home appliances, where the right view is a mirror image of the left view; reproduction 1.7 is an exploded view showing the state where the cover has been detached from the front; reproductions 1.8 to 1.13 are front perspective, front, back, left, top, bottom views in condition that the beam projector has been protruded at the center of the upper part, where the right view is a mirror image of the left view; reproduction 1.14 is a reference view showing an example of a state in which a screen is projected at a central portion of the front from the beam projector at the center of the upper part, and forms no part of the claimed design; this design is for an indoor wall incorporated with built-in home appliances in which various modularized built-in home appliances (such as a beam projector, hub for

(Continued)

home network, hub for IoT, speaker, air purifier, etc.) have been installed, as shown in reproduction 1.7.
